UNITED STATES PATENT OFFICE.

CHARLES A. ROLFE, OF ADRIAN, MICHIGAN, ASSIGNOR TO ROLFE ELECTRIC COMPANY, OF ROCHESTER, NEW YORK, A CORPORATION OF NEW YORK.

ELECTRICAL-CIRCUIT PROTECTOR.

No. 800,833

Specification of Letters Patent.

Patented Oct. 3, 1905.

Application filed July 28, 1904. Serial No. 218,584.

To all whom it may concern:

Be it known that I, CHARLES A. ROLFE, a citizen of the United States, residing at Adrian, in the county of Lenawee and State of Michigan, have invented a certain new and useful Improvement in Electrical - Circuit Protectors, of which the following is a full, clear, concise, and exact description, reference being had to the accompanying drawings, forming a part of this specification.

My invention relates to electrical-circuit protectors for protecting electrical circuits containing the more delicate instruments—such, for example, as telephones, fire-alarm apparatus, and the like—from the unduly strong and dangerous currents from power, lighting, and similar circuits and especially from excessive currents which rise in strength slowly, commonly known as “sneak - currents.”

Prominent objects of the invention are to provide a device of this character which will not require repair or replacement in whole or in part after operation and which will operate with accuracy and effectiveness, to simplify the construction of the same and make such construction practical and durable, and to secure the foregoing and other desirable results in a simple and expeditious manner.

In the accompanying drawings, Figure 1 is a side elevation of an electrical-circuit protector embodying my present invention. Fig. 2 is a longitudinal section of the upper portion of the same on an enlarged scale. Fig. 3 is a transverse section taken on line 3 3 in Fig. 2. Figs. 4 and 5 are views of an interior portion of the device in different positions.

Referring first to Fig. 1, I have shown for carrying out my invention a device comprising a base 1, made of insulating material—such as wood, porcelain, or the like—a pair of line-springs 2 3, secured to and rising from the base 1, and a removable and replaceable device 4, which I shall term a “heat-cartridge,” supported and held in position by the line-springs 2 and 3. The base 1 is provided with binding-posts 5 6, by which the wires of the circuit to be protected can be attached and connected with the line-springs 2 and 3.

The heat - cartridge 4 conveniently comprises a tube 7, made of insulating material—such as hard rubber, fiber, or the like—and made with a large bore 8, open at one end, and

a small bore 9, opening at the other end. A core conveniently consisting of a metallic 55 hood or cap 10 and a block 11 of insulating material, preferably fiber, is fitted within the larger bore 8. The cap 10 is provided with a spindle 12, which extends out through the small bore 9 and projects beyond the end of 60 the tube 7 and has its outer end screw-threaded, and upon this screw-threaded end is fitted a metallic head or terminal 21, which incloses the end of the tube 7 and has an annular groove 22. A bobbin 13 for a coil of wire 14 65 is fitted to the outer end of the block 11, as by means of a threaded shank 15, screwed into said block 11. The coil 14 has one of its ends connected to the cap 10, as shown in Fig. 5, and the other end connected with the 70 bobbin 13. The bobbin 13 is desirably made of metal, and its outer flange 16 is substantially the size of the bore 8, so as to close the end of said bore, as well shown in Fig. 2. A pair of ears 17 17, Fig. 5, are provided on 75 the bobbin 13, being conveniently made integral therewith. A trigger 18 is located with its middle portion between the ears 17 17 and pivoted at its middle point by means of a pin 19, passed through said ears. A small quantity of solder 20, fusible or softenable on a moderate excess of temperature, is placed between the ears 17 17, so as to partially or nearly fill the space between the same, and thus come in contact with and substantially 85 inclose the portion of the trigger 18 which lies between said ears. A metallic collar 23 is fitted over the hollow end of the tube 7, this collar 23 being substantially the size and shape of the portion of the head 21 which 90 incloses the other end of the tube 7, so that the cartridge presents a symmetrical appearance of having two metallic bands upon it—one at each end.

The line-springs 2 and 3 are forked at their 95 upper ends, and the cartridge above described is fitted upon and held in place by said line-springs by passing the ends of the cartridge into the forked portions of the line-springs, the ears 17 17 entering the forked end of the 100 line-spring 3 and the reduced portion of the head 21, formed by the annular groove 22, fitting into the forked portion of the line-spring 2. When so fitted in position, the line-springs 2 and 3 will be held under restraint— 105 that is, their free or upper ends will tend to

spring apart, but will be prevented from so doing by the heat-cartridge 4, the strain being received directly from the line-springs by the head 21 and the trigger 18, whose lower 5 end is in contact with the line-spring 3, as well shown in Figs. 1 and 2. When the device is set, the trigger 18 is in an inclined position, with its lower end in an inward position, as shown in Figs. 1, 2, and 4. As thus arranged 10 and with the heat-cartridge supported by the line-springs and in turn holding them in restraint, the circuit connections are from one side of the circuit to the line-spring 2, from this spring to the head 21, spindle 12, cap 10, 15 heat-coil 14, ears 17 17, trigger 18, and line-spring 3.

The operation of the device is as follows: When the current in the circuit under protection is normal, the device will remain in the 20 condition shown in Figs. 1 and 2, with the circuit closed through it. When, however, the current becomes unduly strong, the heat-coil 14 generates or concentrates sufficient heat to melt or soften the solder 20, whereupon the 25 trigger 18 is released and is swung outwardly by the line-spring 3. This movement of the trigger soon releases the line-spring 3 because of the passage of the upper end of said line-spring from under the lower end of the trigger 30 as the latter attains an inclined position in the opposite direction—that is, as shown by dotted lines in Fig. 2. When so released, the line-spring 3 opens the circuit by breaking the connection between itself and the trigger 35 18. The circuit is thereby opened and the passage of the unduly-strong current is stopped. This constitutes and completes the operation of the device to open the circuit. It is of course necessary in apparatus of this sort to 40 place the protective apparatus in condition for another operation after the trouble with the circuit by which the strong current was permitted to intrude has been removed. In protective apparatus of this general character it 45 has heretofore been customary to replace or repair some part of the apparatus after each operation. By my present device herein shown this, however, is unnecessary. After the device has operated and the circuit been 50 broken the solder 20 obviously cools off and assumes a hardened condition. The trigger 18 has been swung, however, from its original position to an oppositely-inclined position, as indicated by dotted lines in Figs. 2 and 4, 55 so that when the solder hardens the trigger 18 is held by it in this new position as securely as it was held in the original position—that is to say, the device has been automatically resoldered or self-soldered. All that is necessary, therefore, is to turn the heat-cartridge 60 4 one hundred and eighty degrees on its longitudinal axis, by which reversal the trigger 18 is placed in a position corresponding, with reference to the line-spring 3, to its original 65 position. The line-spring 3 is then re-

engaged with the lower end of the trigger, and the device is in normal position again, ready to operate a second time on the passage of an unduly strong current. On the passage of such a current the second time the device 70 again operates as before, swinging the trigger back to its original position in the cartridge 4. Upon the solder again cooling and hardening the heat-cartridge will be again turned on its axis one hundred and eighty degrees, 75 bringing the trigger again into an inwardly-inclined position, after which it will be re-engaged with the line-spring 3. In this way the device can be operated time after time practically without limit. Thus the need of 80 repairs and replacement of parts and the consequent expense, annoyance, and trouble are avoided. It will also be seen that the self-soldering heat-cartridge 4 is of very practicable and desirable construction in that it can 85 be made in separate parts and very readily assembled and can be as easily taken apart to get access to the interior.

In another application of mine, Serial No. 187,041, filed December 29, 1903, I have shown 90 a construction of protector having certain of the broader features of the protector herein set forth, and in said other application I have included claims for such broader features.

It will be understood that changes and 95 modifications can be made in the device herein set forth without departing from the spirit of my invention.

What I claim is—

1. In apparatus of the class specified, a heat-cartridge, comprising a trigger pivoted between its ends and having both ends projecting to permit engagement of either end, and means whereby the trigger is normally held against movement but is permitted to move 105 on the passage of an unduly strong current, substantially as described.

2. In apparatus of the class specified, a self-soldering heat-cartridge, comprising a heat-concentrating member, a trigger pivoted between its ends and having its opposite ends projecting to permit either end to be engaged, and means for holding the trigger normally against movement, said means being adapted to be affected by the heat concentrated in said 110 heat-concentrating member by an unduly strong current to permit movement of the trigger, and to resume its normal condition on the discontinuance of such concentration of heat, whereby the trigger is resecured after being actuated substantially as described.

3. In apparatus of the class specified, a self-soldering heat-cartridge, comprising a trigger pivoted between its ends and having both of its ends adapted to be engaged, a small quantity of material normally hard but softenable on a moderate excess of heat, said material when hard holding said trigger against movement and means for concentrating heat upon the passage of an unduly strong current to 125 130

melt or soften said material, substantially as described.

4. In apparatus of the class specified, a self-soldering heat-cartridge, comprising a trigger pivoted between its ends, and adapted to be engaged on each side of its pivotal point, a small quantity of solder holding the trigger normally against movement, a heat-coil adapted to concentrate heat to melt or soften the solder on the passage of an unduly strong current, and a head forming a means for engaging the opposite end of the cartridge, substantially as described.

5. In apparatus of the class specified, a heat-cartridge comprising a tubular member made of insulating material, a cap or head attached to one end of said member, a core confined within said tubular member and provided with a heat-concentrating coil, a trigger attached to the end of said core and pivoted between its ends which are both adapted for engagement, and a small quantity of fusible or softenable material holding the trigger normally against movement, substantially as described.

6. In apparatus of the class specified, a heat-cartridge comprising a tubular casing 7 of insulating material, a head 21 on one end of said tubular casing, a core within the casing, said core comprising a metallic cap 10 provided with a threaded shank 12 extending through the end of the casing and holding the head 21 in position, a block 11 of insulating material, a bobbin 13 secured to the block 11 and provided with a coil of fine wire 14, ears 17, 17 on the end of the bobbin 13, a trigger 18 located between the ears 17, 17 and pivoted at its middle point, the ends of said trigger extending out beyond the ears 17, 17, and a small quantity of solder 20 holding the trigger 18 normally against movement, substantially as described.

7. In apparatus of the class specified, the combination with means for controlling the circuit, of a heat-cartridge comprising devices for engaging said circuit-controlling means, one of said devices being a trigger pivoted between its ends and having both of its ends

projecting, and means whereby said trigger is held normally against movement but is released upon the passage of an unduly strong current, substantially as described.

8. In apparatus of the class specified, the combination with a pair of line-springs, of a heat-cartridge engaging said line-springs, said cartridge comprising a metallic head for engaging one of the line-springs, and a double-ended trigger pivoted between its ends for engaging the other line-spring, a heat-concentrating member, and a small quantity of softenable material normally hard but adapted to be softened or fused by the heat concentrated in the heat-concentrating member by an unduly strong current, said material when hard holding said trigger against movement substantially as described.

9. In apparatus of the class specified, the combination with a pair of line-springs, of a heat-cartridge comprising a metallic terminal or head, adapted to engage one of the line-springs, a double-ended trigger pivoted between its ends, a small quantity of solder holding the trigger normally against movement, a heat-coil, and a tubular casing of insulation inclosing the heat-coil and extended substantially between the metallic head and the trigger, substantially as described.

10. A heat-cartridge for electrical-circuit protectors having a bodily-removable core carrying a fine-wire heating-coil, and provided with a double trigger pivoted between its ends and having a solder connection with the cartridge.

11. A cartridge for electrical-circuit protectors having a bodily-removable core having a threaded connection for attaching it to the cartridge, said core being provided with a fine-wire heating-coil and also with a double trigger pivoted between its ends and soldered to the cartridge.

In witness whereof I hereunto subscribe my name this 16th day of June, A. D. 1904.

CHARLES A. ROLFE.
